RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

MULTICOLOR MAGAZINE

Application filed October 25, 1928. Serial No. 315,041.

This invention relates to improvements in bobbins usable more particularly in multi-color magazines and it is the general object of the invention to provide means for resisting the tendency of bobbins to rotate on their axes as they await transfer.

In the ordinary stationary magazine the reserve bobbins as they await transfer are stored in parallel vertical stacks and move downwardly by gravity toward transfer position. It is found that due to the vibration of the loom the bobbins tend to turn on their axes and cause either undue slackness or tightness of the filling which extends from the bobbins to the thread holder. It occasionally happens in a magazine of this type that at the time of transfer the filling will be broken and as a result the loom will be stopped by the filling stop motion. It is an important object of my present invention to provide a bobbin so formed that when cooperating with other bobbins of similar type rotation will be prevented.

It is a more particular object of my invention to provide a bobbin the yarn supporting portion of which is non-circular so that the bobbin with its wound mass of weft will have a tendency to remain in a given position with a substantially flat side horizontal.

A more specific object of the invention is to provide a bobbin having a yarn supporting portion which is substantially square in cross section so that the wound mass of weft will have flat sides, the periphery of the bobbin and consequently the length of yarn wound thereupon being somewhat greater than is the case with bobbins circular in cross section.

With these and other objects in view which will appear as the description proceeds, my invention resides in the combination and arrangement of parts hereinafter described and set forth in the claims.

In the accompanying drawings wherein I have shown an embodiment of my invention, Fig. 1 is a vertical transverse section through a two color stationary magazine having bobbins made according to my present invention stored therein,

Fig. 2 is a side view of the bobbin before being wound,

Fig. 3 is an end view of the bobbin taken in the direction of arrow 3, Fig. 2, and

Fig. 4 is a transverse section perpendicular to the axis of the bobbin through the latter when wound with a mass of weft.

Referring to Fig. 1, I have shown a convenient type of magazine for illustrating my invention, said magazine having an inner plate 10 provided with parallel spaced ribs 11 which define vertical compartments C. Cradles 12 are located at the bottoms of the stacks or compartments C and when rocked by mechanism not shown act to pass the lowest bobbin B of the corresponding stack from the latter down the inclined supports 13 toward transfer position.

The ends of the weft from the reserve bobbins are led to a thread holder not shown. The particular type of magazine which may be used in connection with my improved bobbin forms no part of my invention and may be of the usual construction.

In carrying my invention into effect I alter the shape of that part of the bobbin B on which the mass of weft is wound. The bobbins will ordinarily have heads 20 provided with the usual rings 21 and will have a substantially cylindrical feeler or weft detector engaging portion 22. The reduced end of the bobbin extending toward the tip T is made preferably substantially square in cross section as indicated in Figs. 3 and 4. While I have shown a cross section of this particular form yet I do not wish to be limited to the square as any other form which will present a non-circular outline in cross section will suffice, the important feature being that the diameter of the bobbin measured in one direction will be of a different magnitude than the diameter measured in another direction. It is preferable to have the tip end T of the bobbin round as indicated at 23 to facilitate unwinding of the weft.

By an inspection of Fig. 4 it will be seen that the wound mass of weft W will have substantially flat areas F and when the bobbins are stacked in the compartments C they will rotate through a slight angle until opposite flat portions F become horizontal and

contact with corresponding portions of adjacent bobbins.

In the operation of the magazine the bobbins are constrained to move about their axes but with the flat areas F of adjacent bobbins in contact with each other this tendency is resisted with the result that the bobbins pass down the compartments with practically no angular movement about their axes and the aforesaid tightening or slackening of the filling which extends to the thread holder does not occur.

From the foregoing it will be seen that I have provided a bobbin the wound mass of which has a section of non-circular form the effect of which is to prevent the rotation of bobbins as they await transfer in the magazine. It will also be seen that the perimeter of the bobbin will be increased and therefore the amount of yarn which may be unwound thereon is greater than would be the case if the bobbin were cylindrical in cross section.

Having thus described my invention it will be seen that changes and modifications may be made therein by those skilled in the art without departing from the spirit and scope of the invention and I do not wish to be limited to the details herein disclosed, but what I claim is:

30 1. In a weft replenishing mechanism, spaced walls forming a compartment along which bobbins may move towards transfer position and a plurality of superposed bobbins in said compartment, said bobbins being of non-circular section and when wound having outer yarn surfaces of similar non-circular outline engaging each other to resist relative angular movements in said compartment.

40 2. In a weft replenishing mechanism, substantially vertical spaced walls defining between them a compartment along which bobbins may move toward transfer position, and a stack of superposed bobbins in said compartments, each bobbin being so formed as to have substantially flat horizontal outer yarn faces when wound, which faces engage each other to resist relative angular movement of the bobbins.

45 In testimony whereof I have hereunto affixed my signature.

RICHARD G. TURNER.
